(57) CLAIM

The ornamental design for a slider body for slide fastener, as shown and described.

DESCRIPTION

FIG. 1 is a right-front perspective view of a slider body for slide fastener showing our new design;

FIG. 2 is a front-elevational view;

FIG. 3 is a rear-elevational;

FIG. 4 is a right-side elevational view, the left-side elevational view being a mirror image thereof;

FIG. 5 is a top-plan view;

FIG. 6 is a bottom-plan view;

FIG. 7 is a front-elevational view; and,

FIG. 8 is a right-side elevational view.

It being understood that the broken lines of hemispherical projections in FIGS. 1, 2 and 4-8, and the pull tabs in FIGS. 7 and 8 are for illustrative purposes only and form no part of the claimed design.
